UNITED STATES PATENT OFFICE.

CHARLES A. GOULD, OF ST. LOUIS, MISSOURI.

UNDERWEAR-GARMENT.

No. 884,815.

Specification of Letters Patent, Patented April 14, 1908.

Application filed August 21, 1907. Serial No. 389,536.

To all whom it may concern:

Be it known that I, CHARLES A. GOULD, a citizen of the United States, residing at St. Louis, Missouri, have invented a certain new and useful Improvement in Underwear-Garments, of which the following is a full, clear, and exact description, such as will enable others skilled in the art to which it appertains to make and use the same, reference being 10 had to the accompanying drawings, forming part of this specification, in which—

Figure 1 is a front view of an underwear garment constructed in accordance with my invention; Fig. 2 is a side view of said garment; Fig. 3 is a rear view of said garment; Fig. 4 is an enlarged detail view of a portion of the drawers and shirt for the purpose of illustrating more clearly the elastic gusseted opening in the seat of the drawers; and Fig. 5 20 is a sectional view taken on the line 5—5 of Fig. 4.

This invention relates to underwear garments and particularly to that style in which the shirt and drawers are combined in a single garment that are commonly called "union suits". Heretofore, union suits worn for underwear garments have been made of elastic fabric which would stretch to accommodate the movements of the body of the 30 wearer.

The main object of my invention is to provide a union underwear garment constructed principally from non-elastic fabrics such, for example, as muslin, linen, etc. so that the 35 garment will be cool and comfortable. To this end I have devised a union underwear garment comprising a shirt and pair of drawers made of non-elastic fabrics and joined together by a band of elastic knitted material 40 that extends completely around the body of the garment at approximately the waist-line so as to permit free movement of the body of the wearer without restraint.

Another important feature of my underwear garment is a horizontal opening in the 45 seat of the garment that is provided with a gusset of elastic knitted material and which is completely covered by a flap, as hereinafter more fully described.

Referring to the drawings which illustrate the preferred form of my invention embodied in a gentleman's underwear garment, 1 designates a shirt which may have long sleeves, wing or quarter length sleeves, or no 55 sleeves, as shown in the drawings.

2 designates a pair of drawers which may

be of ankle or knee length, both the shirt and drawers being made almost entirely of non-elastic material such as muslin or linen. The drawers are provided with a non-elastic reinforcement or waistband 3 which may either be made of the same material as the drawers or from different material. A strip or band 4 of elastic knitted material is secured to the lower edge of the shirt and to the upper edge 60 of the drawers and to the non-elastic waistband 3, thereby preventing the garment from binding the wearer of same and also eliminating any strain on the garment. The garment is provided with non-elastic facings 65 on the two sides or edges of the front opening, said facings terminating at the upper and lower edges of the elastic knitted band 4. This strip or band 4 of elastic knitted material extends completely around the body of 70 the garment and is not crossed by the facings 75 11 that extend down the two sides of the front opening of the garment. The advantage of having the facings terminate at the edges of the elastic band 4 will be obvious for 80 if these non-elastic facings 11 crossed the elastic knitted band or strip 4 said band would lose its usefulness and be non-elastic in one of the two most important places of the garment where elasticity is necessary. 85

The garments of this general style which have heretofore been used were provided with facings or reinforcing non-elastic strips that extended on both sides of the opening in the front of the garment from the neck of the 90 shirt portion to the crotch of the drawers and crossed the elastic knitted connecting band so that there was not a perfect elastic connection between the shirt and drawers in the front of the waistline. 95

As previously stated, the non-elastic facings 11 of my improved garment do not extend across the elastic knitted band 4 so that there is a perfect elastic connection between the shirt and drawers around the entire waistline. 100

The seat of the drawers portion of the garment is provided with a horizontal opening that is completely closed by a flap or curtain 6 formed by extensions of the rear sides of 105 the leg sections 2, said extensions being joined together by an elastic knitted band or seam 7 so as to produce a wide flap which overlaps the portions 8 of the leg sections 2, as shown in dotted lines in Fig. 3, said flap 110 being held in position by buttons or other suitable devices located adjacent the elastic

knitted waist-band 4. While I prefer to provide the flap 6 with an insert 7 formed of elastic knitted material, it will, of course, be understood that this insert could be omitted 5 without departing from the spirit of my invention. The portions 8^a of the leg sections 2 of the drawers which lie under the flap 6 are joined together adjacent the elastic knitted waist-band 4 by means of an elastic knitted 10 gusset 9, as shown clearly in Fig. 4, so as to permit the seat opening to expand and contract. This feature of providing a garment formed of non-elastic material with an elastic seat opening, I believe is broadly new 15 and produces a garment which is a decided improvement upon those which have heretofore been in use. The elastic knitted gusset 9 in the back of the upper portion of the drawers is stitched to the upper edge of the 20 drawers but is not fastened to the elastic knitted waist-band 4, said gusset crossing said band 4 and being secured to the lower edge of the shirt, as shown in Figs. 4 and 5, the portion of the gusset which crosses but is 25 not connected to the band 4, being designated by the reference numeral 10 in said figures. This strengthens the back of the garment and at the same time serves as a limit to the excessive strain and almost constant 30 expansion of the elastic knitted waist-band in the back of the garment. Said gusset 9 is preferably doubled but not necessarily so, and the extension 10 preferably consists of a single ply or thickness of material. Instead of providing the drawers with 35 a single gusset 9, as herein shown, they could be provided with a plurality of gussets without departing from the spirit of my invention. The drawers may be spliced by strips 40 5 of elastic knitted material to impart a certain amount of elasticity to the drawers, and the shirt portion may also be provided with elastic knitted inserts or strips for the same purpose, but said elastic knitted inserts are 45 not at all necessary and could be omitted if desired.

From the foregoing it will be seen that I have provided a one-piece underwear garment or union suit which is made of non-elastic fabrics, such as muslin, and which is so constructed that it will not bind or draw the person wearing the garment, said garment being preferably made of light-weight fabrics so that it will be cool and comfortable. The 50 complete and all-elastic knitted waistband 4 gives plenty of freedom to the wearer of the garment and the flap or drop-seat closing an elastic seat opening is a feature that has never before been used in union underwear 55 garments made of non-elastic fabrics.

Having thus described my invention, what I claim as new and desire to secure by Letters Patent is:

1. A one-piece underwear garment, consisting of shirt portion and drawers portion

made of non-elastic material and connected together by a strip or band of elastic knitted material, a flap covering an opening in the seat of the drawers portion, and a gusset of elastic knitted material inserted in the 70 drawers portion above the opening in the seat thereof so as to permit the seat opening to expand and contract; substantially as described.

2.-A one-piece underwear garment comprising a shirt portion and drawers portion made of a non-elastic material, facing pieces of non-elastic material extending down each side of the front opening of the shirt portion and drawers portion, a band or strip of elastic knitted material secured to the lower edge of the shirt portion and to the upper edge of the drawers portion to connect them together and extending completely around the body of the garment, the non-elastic 80 facing pieces terminating respectively above and below said elastic knitted waistband and the drawers portion being provided with a horizontal seat opening, a flap or drop seat covering said opening, and one or more 85 gussets of elastic knitted material inserted in the upper back sections of the drawers portion above and around the said horizontal opening to permit said opening to expand and contract, said gussets extending upwardly to the elastic knitted waistband; 90 substantially as described.

3. A one-piece underwear garment comprising a shirt portion and drawers portion made of non-elastic material, facing pieces 100 of non-elastic material extending down each side of the front opening of the shirt portion and drawers portion, a band or strip of elastic knitted material connecting the shirt portion and drawers portion together and 105 extending completely around the body of the garment, said non-elastic facing pieces terminating respectively above and below said elastic knitted waistband or strip and the drawers portion being provided with a horizontal seat opening, a flap or drop seat covering said opening, and one or more gussets 110 of elastic knitted material inserted in the upper back sections of the drawers portion above and around the horizontal opening in 115 the seat, said gusset or gussets extending upwardly to the elastic knitted waistband or strip and passing across same and terminating at the lower edge of the shirt portion to which it is fastened, the portion of the gusset 120 which crosses said elastic knitted strip or waistband being arranged on the inside of same and secured only at the upper and lower edges of said waistband; substantially as described.

4. A one-piece underwear garment, comprising a shirt and drawers made of non-elastic material, a band or strip of elastic knitted material connecting the shirt and drawers together, a flap covering an opening 125

in the seat of the drawers, and a gusset of elastic knitted material inserted in the drawers adjacent the upper edge thereof to form an elastic opening for the seat, the 5 material which forms said gusset extending upwardly across said strip or band and being secured to the lower edge of the shirt; substantially as described.

In testimony whereof I hereunto affix my signature in the presence of two witnesses, 10 this sixteenth day of August 1907.

CHARLES A. GOULD.
